UNITED STATES PATENT OFFICE

MILTON SMALL, OF BROOKLYN, NEW YORK

FIBROUS CONTAINER

Application filed February 5, 1927. Serial No. 166,047.

The invention relates, as indicated by this title, to containers and falls within the general type of containers known as folding or knock down boxes.

5 The device, as herein defined, is particularly applicable for use in packing and transporting clothing where boxes of considerable size are required.

10 The invention, however, is not limited to these clothing boxes, as its features may be applied to any size desired.

15 The main object of the invention is to provide a box which will have a base rigid enough to stand upright without sagging when it is once opened up from the folded or flat position.

Referring to the drawings:

Figure 1, is a plan view of a blank indicating the folds and creasings for a cover.

20 Figure 2, illustrates the cover of Figure 1, completed and folded.

Figure 3, illustrates the cover in perspective when open.

Figure 4, is a view similar to Figure 1, illustrating the blank for the main receptacle.

25 Figure 5, illustrates the blank of Figure 4, with its parts secured and folded in a knock down or flat position.

Figure 6, is a perspective view of the complete receptacle without the cover.

30 Figure 7, is a fragmentary view illustrating the end partially folded, prior to assuming position of Figure 6.

In knock down boxes, particularly those for packing and transporting clothing, it has been customary to make a top and bottom similar to the form illustrated in the cover of Figures 1 to 3, but without providing crease lines to permit folding down the parts so that 35 the empties may be transported in the flat, and in bundles.

It has been a practice to make up boxes with the top and bottom of the general form of Figs. 1 to 3, with securing means for the 40 interned overlapping portions so that the top and bottom, would telescope one with reference to the other. Such boxes have had to be shipped to the consumer or user as complete boxes. This, necessarily, has required a good 45 deal of space for packing and storing.

Necessity for so making the boxes as complete units was to give the necessary strength and stability so that the user could readily pack his goods therein.

55 Any form of folding receptacle which could be shipped in the flat has, so far as applicant knows, been too unstable. As a result, a base or receptacle portion of the box, when laid on the bench for packing, would sag out at the ends requiring a good amount 60 of time for adjusting and holding while the covers were applied.

65 It is not so essential that the covers have such great strength, but the bases must be firm and strong.

With these motives in mind, the present invention has been developed to give a bottom receptacle of unusual strength and stability, when opened from a folded or flat position to that in which it is to be used for 70 filling.

75 Of course, it is possible and intended to use a base form such as illustrated in Figs. 4 to 6, both for the base and cover where extra strength is required, but for ordinary purposes, the lighter form of cover of Figs. 1 to 3, may be employed with the base form of Figs. 4 to 6.

In the accompanying drawings, Figures 1 to 3, 1, indicates a blank of substantially rectangular form, which is slit at its corners, as at 2, 3, 4, 5. These slits extend in to the blank to the juncture of the crease lines 6, 7, 8, 9.

80 The crease lines, illustrated by dotted lines, indicate the size of the cover when the sides and ends are folded up.

85 There are also crease lines 10, 11, 12, 13, formed substantially at right angles to the slits 2, 3, 4, 5.

The blank is then folded on the crease lines 6, 7, 8 and 9, leaving the sides 14, 15, in raised position with reference to the bottom of the portion of the blank, the ends, 16, 17, are then bent upward forming a rectangular 90 receptacle cover.

95 The end portions between the slits 2, 3, 4, 5, and the fold lines 6, 7, 8, 9, are turned in and the side portions between the slits 2, 3, 4, 5, and crease lines 7, 9, are folded about the end as illustrated in Figure 3. When in this 100

position, firmly stapled by clips, 18, or otherwise suitably secured, the crease lines 10, 11, 12, 13, now permit the laying down of the sides 14, 15, upon the base, giving the form 5 illustrated in Fig. 2. Thus, the devices may be shipped in the flat, in shocks, occupying a comparatively small space.

In Figs. 4 to 6, of the drawings, the main receptacle 1, has quite an entirely different 10 arrangement of folds and creasings to give greater stability to the bottom section of the container.

In Figure 4, is illustrated the blank, which is not slit diagonally from the corners, as 15 indicated in Figure 1, but has longitudinal creasings *a*, *b*, and transverse creasings *c*, *d*. These creasings extend the entire length and breadth of the blank so there are formed 20 corner sections that are united along the lines of the creases respectively with the portions 25 of the blank that constitute the sides and the ends of the box or receptacle. It will be noted that the blank is uncut and that its several parts—the bottom, the sides, the ends and the corner sections—are all complete 30 and are integral one with the other. From the intersection of the creasings *a*, *b*, and *c*, are diagonal creasings *h*, *g*, at one end of the blank, and from the creasings *a*, *b*, and *d*, 35 there are diagonal creasings *e*, *f*, at the opposite end of the blank.

The sides *i*, *k*, beyond the creasings *a*, *b*, 35 and the corner sections are folded in against the blank and are firmly secured thereto by staples, eyelets, or other securing means as *j*, (Figs. 5 and 6) the securing means being arranged along the end edges of the corner sections thus uniting such edges to the ends. This forms the knock down as illustrated in 40 Fig. 5.

The diagonal creasings *e*, *f*, *g*, *h*, are made from the bottom of the blank and as a result, when the knock down form of Fig. 5 is 45 opened by raising the sides *i*, *k*, these creasings permit a folding of the ends of the blank into the position illustrated in Figure 6, giving a three ply corner for the end of the receptacle, formed by the corner section of the blank, the folded-over triangular section of 50 the end which is bounded by one of the diagonal creases, and the end section proper against which the folded part rests with a comparatively short intermediate section.

This method of folding and fastening 55 secures a rigid structure which, when opened up from the folded blank of Figure 5, gives the stiff receptacle of Figure 6.

The stiffening at the ends by having the 60 plies secured and folded, as indicated, holds the box ends firmly in upright position, there being no tendency while the box is being filled, of the ends sagging back.

Fastening devices for the end of the receptacle are not of tremendous importance, but 65

are herein illustrated to show the means of giving continual permanency.

Obviously, various forms of fastening means might be employed, if desired, although the mere folding and creasing of the structure is such as to give it stability as hereinbefore indicated.

There is illustrated in Figs. 6 and 7, a 70 novel arrangement for holding the ends of the box in position and at the same time securing the contents of the package. This arrangement has particular advantages when used in the clothing trade where it is desirable to tie down the contents of the box 75 after it is filled.

To effect the result, the eyelets are placed as at 1', 2', 3', 4', in the folding portions of the blank and a central eyelet 5', is arranged at the lower edge of the end fold.

Eyelets 6', 7', 8', 9', are arranged in the 80 side folds and bottom at some little distance from the end fold.

A cord or tape 10', is passed through the eyelets 1', 2', 3', 4', and the two ends of the cord are then passed through the eyelet 5', 90 then they are passed through the eyelets 7', 9', in the bottom of the box and back through the eyelets 6', 8', in the sides.

This arrangement of cords and eyelets 95 forms a sort of "bridle" which permits the box to be folded down, as indicated in Figure 5, and when opened up as illustrated in Figs. 6, and 7, the cords are pulled tightly 100 and tied over the contents of the box, thus they firmly secure the ends in upright position and hold the contents.

Of course, the two ends of the cord might be tied together or secured in any suitable manner without being used to tie in the contents. They would then serve to hold the box 105 firmly in upright position without reference to also holding down the contents of the box.

Obviously, the exact form and arrangement of the folds and parts of the box may 110 be modified to suit the requirements, but the main feature is to provide a box blank slit and creased so that it may be folded and securely fastened as to certain of its elements and then again folded to provide a receptacle 115 of suitable size.

What I claim as my invention and desire to secure by Letters Patent is:

1. A container formed from a rectangular blank of material that is longitudinally and 120 transversely creased parallel with the edges thereof to form the sides and ends of the container, the creases extending to the edges of the blank and intersecting to form corner sections, which latter are integral and united 125 with both the sides and the ends, the sides and corner sections being folded inwardly on the longitudinal crease lines so the corner sections overlie the ends, and when thus folded the corner sections being united with 130

the ends near the free edges of the latter, and the ends being diagonally creased form the intersections of the longitudinal and transverse creases of the blank to the free corners of the overlying corner sections.

5 2. A container formed from a paper blank creased parallel to its sides to form the sides and ends of the container, the sides and ends being connected with each other by integral
10 corner sections arranged to be folded over the ends when the box is set up, and a binding cord that passes through the said folding over portions and also through the ends proper at points intermediate the folded over
15 portions, and which, after passing through the ends also passes through the bottom of the container from the inside to the outside, and then from the outside through the sides of the container to the inside of the latter
20 whereby said parts may be drawn together and held in set up position on the tightening of the cord.
